US00D904968S

(12) **United States Design Patent** (10) **Patent No.:** **US D904,968 S**
(45) **Date of Patent:** **** Dec. 15, 2020**

(54) **BROADCAST SOWING DEVICE**

(71) Applicant: **GUANGZHOU XAIRCRAFT TECHNOLOGY CO., LTD.**,
Guangzhou (CN)

(72) Inventor: **Pan Jiang**, Guangzhou (CN)

(73) Assignee: **GUANGZHOU XAIRCRAFT TECHNOLOGY CO., LTD.**,
Guangzhou (CN)

(**) Term: **15 Years**

(21) Appl. No.: **29/709,366**

(22) Filed: **Oct. 14, 2019**

(30) **Foreign Application Priority Data**

Apr. 23, 2019 (CN) 2019 3 0189916

(51) **LOC (12) Cl.** **12-07**

(52) **U.S. Cl.**

USPC **D12/345**; D15/13

(57) **CLAIM**

The ornamental design for a broadcast sowing device, as shown and described.

DESCRIPTION

FIG. 1 is a front elevation view of a broadcast sowing device according to my design;

FIG. 2 is a rear elevation view of thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a third perspective view thereof; and,

FIG. 10 is a fourth perspective view thereof.

1 Claim, 10 Drawing Sheets
